UNITED STATES PATENT OFFICE

SERN L. HANSEN, OF CLEVELAND, OHIO

DESIGN FOR A TABLE KNIFE

Application filed April 16, 1930. Serial No. 35,262. Term of patent 7 years.

To all whom it may concern:

Be it known that I, SERN L. HANSEN, a citizen of the United States, whose post-office address is 411 Citizens Building, in the city of Cleveland, county of Cuyahoga, and State of Ohio, have invented a new, original, and ornamental Design for Table Knife, of which the following is a specification, reference being had to the accompanying drawing, forming part thereof.

Fig. 1 is a plan view of a table knife showing my new design; and Fig. 2 is a side elevation of the same.

I claim:

The ornamental design for a table knife, as shown.

SERN L. HANSEN.
